UNITED STATES PATENT OFFICE.

SANFORD D. LELAND, OF WELLESLEY, MASSACHUSETTS, ASSIGNOR TO MANUFACTURING EQUIPMENT & ENGINEERING COMPANY, OF FRAMINGHAM, MASSACHUSETTS, A CORPORATION OF MASSACHUSETTS.

BUBBLING FOUNTAIN.

Application filed May 2, 1921. Serial No. 466,051.

To all whom it may concern:

Be it known that I, SANFORD D. LELAND, a citizen of the United States, resident of Wellesley, county of Norfolk, State of Massachusetts, have invented an Improvement in Bubbling Fountains, of which the following description, in connection with the accompanying drawing, is a specification, like characters on the drawing representing like parts.

This invention relates to bubbling fountains and particularly to bubbling fountains of that type which are provided with means for cooling the water before it is delivered from the bubbler.

One feature of the present invention relates to a novel bubbling fountain by which the cold waste water which is discharged from the bubbler may be used to pre-cool the supply water before it is delivered to the cooling means.

In bubbling fountains of this type there is always a certain amount of water discharged from the bubbler which is not used and in the case of ice-cooled bubbling fountains such waste water is at a considerably lower temperature than the water supplied to the cooling means. My invention contemplates the provision of means whereby such waste water may be used to decrease the temperature of, or pre-cool, the supply water before it is delivered to the cooling means. An advantage which results from this construction is that considerably less ice will be required to cool the water than is required where no pre-cooling takes place.

In order to give an understanding of my invention I have illustrated in the drawings a selected embodiment thereof which will now be described after which the novel features will be pointed out in the appended claims.

Fig. 1 of the drawings is a sectional view of a bubbling fountain embodying my invention.

Fig. 2 is a fragmentary sectional view taken through the inlet pipe to the pre-cooler.

In the drawings I have shown at 1 a bubbler of any suitable or usual construction to which the water is supplied through a pipe 2, the latter having a valve 3 therein by which the water may be turned on or shut off.

The type of bubbling fountain herein illustrated is the ice-cooled type and it comprises a cooling coil 4 which receives water from a suitable source of supply and delivers it to the valved connection 2 leading to the bubbler 1. This cooler 4 is shown as encircling a tank 5 in which ice may be placed, said tank having the removable cover 6 through which the ice may be delivered thereto. The cooling coil 4 is shown as closely encircling the tank 5 and as enclosed in a suitable heat insulating casing to prevent a loss of heat by radiation. The heat insulating casing herein shown comprises two concentric shells 7 and 8 which encircle the cooling coil 4 and which are spaced apart, the space between them being filled with some insulating material 9. These concentric shells 7 and 8 are shown as secured at their lower ends to a lower head 10 and at their upper ends to an upper head 110, said head having the opening therein leading to the tank 5 and which is closed by the cover 6.

With this construction the water will be cooled as it passes through the cooling coil 4 so that the water which is delivered from the bubbler will always be ice-cooled water.

The parts thus far described are, or may be, all as usual in ice-cooled bubbling fountains and form no part of my present invention.

In accordance with the present invention I have provided means whereby the waste water which is discharged from the bubbler 1 may be utilized to pre-cool the water which is delivered to the cooling coil 4 and in the preferred embodiment of my invention I accomplish this by providing a pre-cooling coil which is connected to the water supply and which is also connected to the cooling coil 4 so that the water supplied to the bubbler will pass through the pre-cooling coil before it is delivered to the cooling coil.

The pre-cooling coil is arranged to be cooled by the waste water delivered from the bubbler 1 and this can conveniently be done by placing said cooling coil in a chamber to which such waste water is delivered, said chamber preferably having a suitable overflow leading to the drain. With such an arrangement it is possible to reduce the temperature of the water several degrees before it is delivered to the cooling coil 4 and

therefore the work which the ice has to do in cooling the water for the bubbler is greatly reduced thus effecting a considerable saving in the quantity of ice required.

5 In the construction herein illustrated the pre-cooling coil is indicated at 11 and it is connected at its upper end to the lower end of the cooling coil 5 through a suitable connection 12. The lower end of the pre-cooling coil connects to the water supply through a supply pipe 13. This pre-cooling coil is shown as arranged in a chamber 14 constructed to receive the waste water delivered from the bubbler 1.

10 There are various constructions which may be adopted to provide for such a chamber to contain the pre-cooling coil and receive the waste water. A desirable construction is illustrated in Fig. 1 wherein the chamber 14 is situated beneath the ice tank 5 and within the same casing as that which contains the ice tank and cooling coil. The casing including the concentric shells 7 and 8 with their intermediate insulation 9 is 15 extended below the ice tank 5 and cooling coil 4 to provide sufficient room for the pre-cooling coil 11 and the chamber 14. This chamber is herein shown as an annular chamber formed between the lower end of the shell 7 and a cylindrical member 15 situated beneath the ice tank. The bottom of the chamber 14 is formed by a plate 16 20 extending across the shell 7 and supported on the lower head 10.

25 The bubbler 1 is provided with a waste pipe 17 which extends down between the shells 7 and 8 and is therefore surrounded by the insulating material 9. This waste pipe 17 leads to a connection 18 that extends up through the head 10 and plate 16 and communicates with the chamber 14. The chamber 14 is provided with an overflow pipe 19 which extends through the bottom thereof and is connected to the drain by 30 means of a connection 20. This connection 20 leads into the chamber 22 formed in the base 21 on which the fountain is supported and the chamber 22 is connected by a pipe 23 with the drain. The upper end of the 35 overflow pipe 19 is situated adjacent the top of the chamber 14 and as a result the chamber 14 will be always filled with the waste water from the bubbler 1. With this construction the pre-cooling coil 11 is situated in a chamber which is filled with the cool waste water from the bubbler 1 and as a result the water in the pre-cooling coil 11 will have its temperature considerably reduced before it is delivered to the cooling coil 4. It will, therefore, require less ice to cool the water in the cooling coil 4 and the device illustrated therefore acts as an

ice economizer. The waste pipe 17 is shown as having a connection 24 leading directly to the chamber 22, said connection being controlled by a valve 25. This connection 24 constitutes a drain connection by which the chamber 14 and drain pipe 17 may be drained.

40 26 indicates a drain pipe connected to the bottom of the ice tank 5 and leading through the lower head 10 into the chamber 22, said drain pipe being provided with a suitable valve 27. This drain pipe is for the purpose of draining the water from the 45 ice tank 5. The stand 21 is formed with an opening 28 through which the valve 27 is accessible.

29 indicates an air chamber connected to the pipe connection 2 for the purpose of 50 preventing water hammer in case the valve 3 is suddenly closed.

I claim.

1. In a bubbling fountain, the combination with a casing having double walls with 55 the space between the walls filled with insulation, of a partition extending across said casing, an ice-containing vessel above the partition and forming with the walls of the casing an annular space, a cooling coil 90 in said space encircling said vessel, said casing having another annular chamber beneath the partition, a pre-cooling coil in the latter annular chamber connected to the cooling coil and communicating with a 95 source of supply, a bubbler connected to the cooling coil, a waste pipe from the bubbler located between the walls of the casing and communicating with said annular chamber beneath the partition, and an overflow pipe 100 for taking the overflow from said annular chamber.

2. In a bubbling fountain, the combination with a casing having double walls with 105 the space between the walls filled with insulation, of a partition extending across said casing, an ice-containing vessel above the partition and forming with the walls of the casing an annular space, a cooling coil in said space encircling said vessel, said 110 casing having another annular chamber beneath the partition, a pre-cooling coil in the latter annular chamber connected to the cooling coil and communicating with a 115 source of supply, a bubbler connected to the cooling coil, and a waste pipe extending from the bubbler down between the walls of the casing to a point below the latter and then laterally beneath the casing and 120 up through the bottom thereof to the annular chamber.

In testimony whereof, I have signed my name to this specification.

SANFORD D. LELAND.
